GOLF CLUB GRIP

Clifford A. Spencer, Akron, Ohio, assignor to Eaton
Yale & Towne Inc., Cleveland, Ohio

Filed Mar. 5, 1971, Ser. No. 121,615

Term of patent 14 years

Int. Cl. D21—02

U.S. Cl. D34—5

FIG. 1 is a front elevational view showing my design of a golf club grip.

FIG. 2 is a left side elevational view of the design.

FIG. 3 is a rear elevational view of the design.

FIG. 4 is a top elevational view of the design.

FIG. 5 is a bottom elevational view of the design.

The dashed lines indicate a continuous uniform pattern.

I claim:

The ornamental design for a golf club grip, as shown and described.
